[57] CLAIM

The ornamental cover assembly of a binder with double layer transparent pockets, as shown and described.

DESCRIPTION

FIG. 1 is a perspective view of an illustrative embodiment of my cover assembly of a binder with double layer transparent pockets;

FIG. 2 is a front elevational view thereof;

FIG. 3 is a top elevational view thereof;

FIG. 4 is a bottom view thereof;

FIG. 5 is a left side view thereof;

FIG. 6 is a right side view thereof;

FIG. 7 is a rear elevational view thereof;

FIG. 8 is a cross-sectional view taken along lines 8—8 of FIG. 2;

FIG. 9 is an exploded view thereof;

FIG. 10 is a front elevational view of an alternative embodiment;

FIG. 11 is a front elevational view of another alternative embodiment;

FIG. 12 is a front elevational view of a further embodiment of the invention; and,

FIG. 13 is a front elevational view of yet another embodiment of my cover assembly of a binder with double layer transparent pockets.

The broken line showing of portions of a binder is for illustrative purposes only and forms no part of the claimed design.
